UNITED STATES PATENT OFFICE.

CHARLES A. WARD, OF NEW ROCHELLE, NEW YORK, ASSIGNOR TO WARD MOTOR VEHICLE CO., OF MOUNT VERNON, NEW YORK, A CORPORATION OF NEW YORK.

RUNNING-SWITCH FOR ELECTRIC VEHICLES.

1,242,619.

Specification of Letters Patent.

Patented Oct. 9, 1917.

Application filed March 30, 1917. Serial No. 158,606.

To all whom it may concern:

Be it known that I, CHARLES A. WARD, a citizen of the United States, and a resident of New Rochelle, in the county of Westchester and State of New York, have invented a new and Improved Running-Switch for Electric Vehicles, of which the following is a full, clear, and exact description.

This invention relates to electric switches of the plug and socket type and it has for its general objects to improve and simplify the construction so as to be reliable and efficient in use, of durable and substantial form, and so designed that an effective contact can be maintained between the socket members and plug.

A more specific object of the invention is the provision of a switch having a novel arrangement of socket members into which a tapered plug is inserted, the socket members having on their free ends an encircling ring of insulation for holding the socket members together and serving to adjust them to tighten the socket when the same becomes worn.

Still another object is the provision of means on the plug and socket whereby the insertion of the plug produces a rotary motion to insure an effective electrical connection, and furthermore, the plug is hollow, and entering the bore is a stud of insulation rising from the base on which the socket members are fastened.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views,

Figure 1 is a plan view of the switch with the cover plate, plug and socket member adjusting ring removed;

Fig. 2 is a longitudinal vertical section of the switch in circuit-closing condition;

Fig. 3 is a transverse section on the line 3—3, Fig. 2;

Fig. 4 is a detail sectional view on the line 4—4, Fig. 1; and

Fig. 5 is a detail sectional view on the line 5—5, Fig. 1.

Referring to the drawing, 1 designates a support on which is fastened a casing or box 2 of the switch, the latter having an opening 3 at one side for the cable to enter 60 the box. The top of the box has an opening 4 for permitting access to the interior for assembling the parts, the top opening 4 being normally closed by a cover plate 5. In the bottom of the box 2 is secured by bolts 65 6 a block of insulation 7, and on this is fastened the spaced socket members 8 and 9 which are approximately semi-cylindrical and oppositely disposed so that together the said members constitute a socket which tapers downwardly. Insertible in the socket 70 is a tapering plug 10, which, like the socket members, is of conducting material, and on the upper end of the plug is a T-shaped handle 11 for convenience in inserting or removing the plug. The members 8 and 9 are provided with external threads 12 on which is screwed a fiber ring 13 which serves to keep the outer ends of the members 80 in proper relation, and which enables the members to be drawn together to compensate for wear. The socket members have on their base portions terminal sockets or equivalent means 14 for receiving the wires of the cable which enters the box through 85 the opening 3, the said conductor sockets 14 being at the side of the switch socket nearest the opening 3. The cover 5 has an opening 15 through which the plug 10 and ring 13 project. If desired, the socket members 90 may be formed with coarse-pitched grooves 16, and on the plug 10 are lugs 17 to enter the grooves, so that as the plug 10 is inserted it has a rotary motion whereby a wiping engagement between the socket 95 members and plug is produced, whereby the best electrical connection is obtained between such parts. The plug 10 has a chamber 18 into which projects a stud 19 of insulation, which rises from the block 7.

From the foregoing description taken in connection with the accompanying drawing, the advantages of the construction and method of operation will be readily understood by those skilled in the art to which the invention appertains, and while I have described the principle of operation, together with the device which I now consider

to be the best embodiment thereof, I desire to have it understood that the device shown is merely illustrative and that such changes may be made when desired as fall within 5 the scope of the appended claims.

Having thus described my invention, I claim as new and desire to secure by Letters Patent:

1. A switch comprising a pair of socket 10 members insulated from each other, a plug insertible between the members, and means separate from the plug and adjustably connected with the members for holding the same together and for compensating for 15 wear of the plug and members.

2. A switch including a pair of members, a plug insertible between the members, and a ring of insulation for adjustable connection with the members for holding the same 20 against spreading apart and for adjusting the members toward each other in compensation for wear.

3. A switch including spaced socket members, a plug insertible between the members, 25 and a ring of insulation having a threaded

connection with the free extremities of the socket members for holding the same in proper relation to each other.

4. A switch including a pair of socket members, a body of insulation on which the members are mounted and having a stud extending upwardly between the members, and a plug insertible between the members and having a chamber into which the stud extends. 30

5. A switch including a plurality of socket members, a plug insertible between the members, and means between the plug and members for producing a rotary motion of the plug during insertion or removal. 35

6. A switch including a plurality of socket members, a plug insertible between the members, means between the plug and members for producing a rotary motion of the plug during insertion or removal, and 40 means acting simultaneously on the socket members for holding the same in proper relation to each other.

CHARLES A. WARD.
